UNITED STATES PATENT OFFICE.

JAMES CHARLES POTTER, OF PAWTUCKET, RHODE ISLAND.

EVENER FOR COTTON-OPENING MACHINES, &c.

1,072,649.

Specification of Letters Patent.

Patented Sept. 9, 1913.

Application filed April 19, 1912. Serial No. 691,941.

To all whom it may concern:

Be it known that I, JAMES C. POTTER, of Pawtucket, in the county of Providence, and in the State of Rhode Island, have invented 5 a certain new and useful Improvement in Eveners for Cotton-Opening Machines, &c., and do hereby declare that the following is a full, clear, and exact description thereof.

Cotton opening machines are provided 10 with an evening mechanism that automatically regulates the speed of the feed roll to suit the thickness of cotton delivered thereto the aim being that, regardless of the thickness or number of laps received by the feed 15 roll, the lap delivered as the product of the machine will be of uniform gage. Said evening mechanism comprises a pair of cone drums belted together, one of which cones is geared to the feed roll, and the other to a 20 source of power, and the belt is automatically shifted along the cones to vary the speed of the driven cone and hence that of the feed roll. Such a mechanism is shown in my Patent No. 1,015,508 issued January 25 23, 1912. Heretofore in order to vary the thickness of lap delivered by the machine, which is determined by the normal speed of the feed roll, that normal speed has been fixed by adjusting the belt of the cone gear- 30 ing at a point to secure the desired normal speed. This point might be anywhere along the cones, and so near the ends thereof as to allow but little automatic movement of the belt in one direction and hence diminish 35 materially the scope of automatic variation of the speed of the feed roll, with the result that an abnormal thickness, or an abnormal thinness of cotton delivered to the feed roll could not vary the speed of the feed roll to 40 meet the condition, so that the product de- livered by the machine would be defective.

The principal object of my invention is to obviate this condition, and render available 45 the travel of the cone pulley belt the entire length thereof for the automatic control of the speed of the feed roll.

In the accompanying drawings—Figure 1 is a view partly in vertical section and partly in side elevation; Fig. 2 is an end 50 elevation thereof.

Referring to the drawings the evener mechanism shown, as in the case of my patent referred to, comprises two cones 10 and 11, and a belt 12 that is shiftable along

the same by the action of a system of scale 55 levers, not necessary to be described as the construction and operation thereof are usual. On one end of the shaft of the upper or driven cone, is a pinion 13 which is removably secured to the shaft so that pinions of 60 different size may be employed and, hence, the speed of the gear 14 with which such pinion meshes, be varied. A change gear- 65 ing is thus provided, and as is usual with change gears, the wheel 14 is journaled on a yoke 15 hung concentric with the shaft 16 of the gear 17 which, through a pinion 18, receives motion from the wheel 14. The gear 17 is the pinion carrier of a differential gear of usual construction, including a 70 ratchet wheel 19 on the shaft 16, adapted, when motion is to be imparted to the shaft 16 from the differential gear, to be held by a pawl 200. The ratchet wheel 19 by a sleeve 20, is connected with the gear 21 with which 75 the planet pinion 22 meshes as well as with the sun gear 23 keyed to the shaft 16. The pawl, at will, may be rocked into and out of ratchet wheel-engaging position by a suitable handle connected with a rod 24, 80 which is attached to the pawl. On the shaft 16, is a bevel pinion 25 in mesh with a bevel gear 26 on the shaft 27 of the usual feed roll 28.

It will be seen that the running of the 85 feed roll is wholly under the control of the pawl, and as the latter is very light, but little effort is required to move it to engage the ratchet wheel to place the feed roll in 90 operation, and to disengage the ratchet wheel to deprive the feed roll of power.

To secure variation in the weight or thickness of lap delivered from the machine, all that is necessary is to change from a pinion of one size on the driven cone shaft to one 95 of a different size, and not shift the belt of the cones at all, and hence, the latter for its normal position is always at midlength of the cones so that the entire range of automatic change of feed roll speed, which the 100 length of the cones affords, is available, and automatic control of thickness of the finished lap is secured under extremes of variation not possible where the normal speed of the feed roll is obtained by adjusting the 105 belt of the cone gearing.

I employ no worm gearing between the driven cone and the feed roll, and, hence,

endwise pressure from that source being eliminated, the sensitiveness of the evener is increased.

Having thus described my invention what 5 I claim is—

1. In an evener mechanism for cotton openers, etc., the combination of the feed roll thereof, a belt and cone gearing, the belt being automatically shiftable along the 10 cones, and means independent of shifting the belt for varying the speed of the roll relative to the driven cone.
2. In an evener mechanism for cotton openers, etc., the combination of the feed 15 roll thereof, a belt and cone gearing, the belt being automatically shiftable along the cones, and a change gear connection between said feed roll and the driven cone.
3. In an evener mechanism for cotton 20 openers, etc., the combination of the feed roll thereof, a belt and cone gearing, the

belt being automatically shiftable along the cones, a differential gear connection between the feed roll and the driven cone having a pawl and ratchet, and means to operate the 25 pawl of the differential gear to control the running of the feed roll.

4. In an evener mechanism for cotton openers, etc., the combination of the feed roll thereof, a belt and cone gearing, the 30 belt being automatically shiftable along the cones, and a change gear connection between said feed roll and the driven cone, comprising a train of gears that includes a removable pinion on the cone shaft and a shiftable 35 intermediate gear meshing with the pinion.

In testimony that I claim the foregoing I have hereunto set my hand.

JAMES CHARLES POTTER.
